Primary Examiner — Patricia A Palasik(74) *Attorney, Agent, or Firm* — Taft Stettinius & Hollister LLP(57) **CLAIM**

The ornamental design for a selective compliance assembly robot arm, as shown and described.

DESCRIPTION

FIG. 1 is a front view of a selective compliance assembly robot arm;
 FIG. 2 is a rear side view thereof;
 FIG. 3 is a left side view thereof;
 FIG. 4 is a right side view thereof;
 FIG. 5 is a top view thereof;
 FIG. 6 is a bottom view thereof;
 FIG. 7 is a perspective view thereof;
 FIG. 8 is another perspective view thereof;
 FIG. 9 is another perspective view thereof; and,
 FIG. 10 is another perspective view thereof.
